UNITED STATES PATENT OFFICE

135,851

DESIGN FOR A NONSKID TIRE

Edward Hayes, Wickliffe, Ohio

Application September 14, 1942, Serial No. 108,229

Term of patent 14 years

To all whom it may concern:

Be it known that I, Edward Hayes, a citizen of the United States, residing at 1167 E. 294th Street, Wickliffe, in the county of Lake and State of Ohio, have invented a new, original, and ornamental Design for a Nonskid Tire, of which the following is a specification, reference being had to the accompanying drawing forming part thereof.

The Figure 1 is a perspective view of the tire, a portion being illustrated in dotted lines, showing my new design; and

The Figure 2 is a fragmentary plan view thereof.

I claim:

The ornamental design for a nonskid tire, as shown.

EDWARD HAYES.
